UNITED STATES PATENT OFFICE.

GEORGE H. AUSTIN, OF HAMMOND, INDIANA, ASSIGNOR TO AMERICAN STEEL FOUNDRIES, OF CHICAGO, ILLINOIS, A CORPORATION OF NEW JERSEY.

METHOD OF MAKING FULCRUMS.

Application filed August 27, 1926. Serial No. 131,946.

My invention relates to improvements in the process of forming brake beam fulcrums for use on railroad cars.

The type of brake beam fulcrum contemplated in my invention is used as a strut positioned between and intermediate the length of a compression member and a tension member to form a trussed break beam structure. Fulcrums of this type are usually made of forged steel and have two parallel arms, the intermediate portions of which are twisted in an inclined plane forming an angularly disposed slot and are further provided with suitable bearing seats at its opposite ends to engage the compression and tension members respectively. The slot between the two parallel arms is adapted to receive a lever mounted on a pin journaled at its opposite ends in bearing holes drilled through the arms.

It has been the practice heretofore to construct brake beam fulcrums out of relatively thin bar stock in order to reduce the expense but at all times selecting material of sufficient thickness and strength to meet the requirements of service to which it is subjected. A marked disadvantage has been encountered, however, in constructing brake beam fulcrums from thin metal stock inasmuch as the thickness does not provide sufficient bearing surface for the lever pivots which are subject to excessive wear as the entire braking strain is imparted to the brake beam and brake shoes from the operating mechanism through the lever pivot referred to. In order to counteract this detrimental effect, it has been the practice to provide annular protrusions or bosses on the outside of the two arms surrounding the bearing holes in a manner to increase the bearing surface, these being formed either by welding additional metal to the arms or by pressing to form bosses so as to increase the bearing surface. This method is also objectionable as it is found in practice to be very difficult to provide bearing surfaces in this manner which are properly aligned and further, because it necessitates a spotting of

the boss of each and every job according to the finish of the brake beam.

It is the purpose of my invention to provide a brake beam fulcrum which may be formed from a relatively small amount of material and yet have ample thickness to provide for bearing holes formed by drilling.

It is the further object of my invention to provide a brake beam fulcrum which has a relatively thick portion to provide for the bearing openings, and a thinner portion to provide for the necessary length with the least possible material.

It is the further purpose of my invention to provide an improvement in the process of making brake beam fulcrums which comprises tapering the arms of the brake beam in a manner to reduce the thickness in a portion where it is not needed so as to increase the length.

Other objects of my invention will be more clearly understood from the following description when considered in connection with the accompanying drawing in which the various figures show the development of my brake beam fulcrum after each step in the process herein set forth.

In the drawings—

Figures 1 to 18 represent the different forms of the fulcrum piece as it will appear after the various steps in the process practiced according to my invention.

My process contemplates shearing a piece of bar milled stock of a thickness sufficient to provide the necessary bearing surface when bearings are formed in drilling, but of a length less than that of the finished product. Such a bar is shown represented at 10 in Figure 1, the edges being shown slightly rounded as it comes from the mill, this last feature being best shown in Figure 2. The bar, which is heated, is then tapered by a rolling operation, squeezing the piece at one end for making the foot portion and reducing the thickness of the stock by causing the metal to flow in a manner to increase the length thereof. This reduction in stock is made below the point where the greatest

pinhole distance is, that is, where the lever pivot is to be positioned; this operation being accomplished in a roll tapering machine in a manner to cause the metal to flow to increase the length of the piece.

After the bar is properly tapered, it is subjected to the first pressing operation at which time the desired stamping is done; then the hole 11 is punched at its tapered end and the outer edge trimmed off round from the gauge at the opposite end so that the length of the piece for forging will be the same each time. This results in the shape such as shown in Figure 5, where the bar is provided with a rounded outer end such as 12, with the reduced foot portion designated 13. The piece is then subjected to a second pressing operation on an edge bend, preparing same for the twisting operation to be explained later. The bends are effected, such as shown in Figures 7 and 8, bend 14 being nearest the foot end and bend 15 being in the same direction at the opposite end. The outer tapered end of the bar is then bent at right angles to the main portion of the bar, such as shown at 16 in Figures 9 and 10, to form a foot for engagement with the brake beam.

The fourth or final pressing operation forms a twist, above referred to, in the piece intermediate its length at the proper degree for the fulcrum, the twist being shown as at 17 in Figures 11 and 12. Thus far, we have formed one of the two necessary arms to complete the brake beam fulcrum.

The next operation contemplates uniting the ends of two arms so formed in a manner to form a tension rod seat. This is done by mounting the two arms in dies having an opening to receive the ends of the blank to be operated upon, upsetting the ends of the blank while at a welding heat, causing the ends to unite forming an integral bearing seat, such as shown at 18 in Figure 13. The relative positions of the two arms after the upsetting operation will be seen in Figure 14, feet 18 extending in opposite directions and the twisted portions for the two arms being parallel, as shown, to form the angular slot designated at 19 in this figure.

The next operation comprises trimming the flash which is thrown up in the prior operation, leaving the fulcrum with a smooth rounded edge 20, as shown in Figure 15. When the fulcrum is completed to this extent, it is then ready to be shipped or to be stocked. The only operation remaining is the drilling of suitable bearing holes, such as shown at 21 in Figure 17, but which are not so drilled until the finish of the particular brake beam to which it is to be applied has been ascertained. This last drilling operation is usually done at the time the brake fulcrum is installed, thus permitting great flexibility in the installation and limit-

ing the necessity of stocking many varieties, the holes of which are positioned differently for installation on varying types of brake beams. This last feature is of great importance inasmuch as the foremost objection to a type of fulcrum having the bossed bearing holes is that it necessitates the manufacture of a great variety of types of fulcrums, inasmuch as the placing and forming of the bearing hole requires an operation at the factory and cannot be accomplished by merely drilling, such as can be done by the mechanic installing the fulcrum, as is possible with my device.

In my invention, I have provided a brake beam fulcrum formed from a minimum of material and yet have provided that portion of the fulcrum which is to accommodate the bearing opening with a thickness which will permit the holes to be drilled and thus render it unnecessary to have this operation completed at the factory before the fulcrum is delivered for installation.

The above detail description and the disclosure in the drawing are illustrative of a preferred embodiment of my invention, but it is my intention to include all modifications that fall within the scope of the appended claims.

I claim:

1. The process of forming a brake beam fulcrum having two parallel twisted arms integral at one end to form a tension rod seat, and having the opposite ends of the arms bent at right angles to form feet, which consists in lengthening the arms by tapering their outer ends and then pressing same to shape and twisting the arms, and finally uniting the opposite ends to form an integral tension rod seat.

2. The process of forming a piece for a brake beam fulcrum which is of proper length and of proper thickness at the places where bearing holes occur which consists in lengthening by tapering an end starting at a point between the location of the bearings and the end of the piece and then boring bearing holes in the portion which is not tapered.

3. The process of forming a brake beam fulcrum which consists in tapering one end of a fulcrum piece to increase its length, then pressing to punch a hole in the tapered end and to round the tapered end of the piece, then pressing to form an edge bend, then bending a right angle foot on the end and twisting the central portion of the piece, then uniting the ends of two pieces at a welding temperature and finally trimming off the flash thrown up in the uniting operation.

4. The process of producing a brake beam fulcrum which consists in providing a brake beam piece of a thickness to provide suffi-

cient bearing surface, then tapering the thickness at one end by pressure causing the metal to flow to increase the length of the piece, then shaping and punching by pressure and finally uniting the opposite ends of two pieces so shaped to form a tension rod seat.

5. The process of forming a brake beam fulcrum which consists in providing two bars of stock of a thickness sufficient to pro-

vide bearing surfaces and shorter than the final length, lengthening said bars by tapering the ends thereof throughout portions removed from the possible locations of bearing holes, pressing the said bars to shape and 15 finally uniting their opposite ends to form an integral tension rod seat.

Signed at Hammond, Indiana, this 21st day of August, 1926.

GEORGE H. AUSTIN.
